[57] **CLAIM**

The ornamental design for a sink pedestal, as shown and described.

DESCRIPTION

FIG. 1 is a perspective view of a sink pedestal showing my new design;

FIG. 2 is an end view, the opposite end being a mirror image thereof, the opposite end being flat and unornamented; and, FIG. 3 is a front elevational view thereof, the perpendicular sides being a mirror image thereof.

The broken line showing is for illustrative purposes only and forms no part of the claimed design.
